LIFTING JACK

Edmund Pachowicz, Chicago, Ill., assignor to
 Templeton, Kenly & Co. Limited, Chicago, Ill.,
 a corporation of Illinois

Application August 14, 1933, Serial No. 684,998

2 Claims. (Cl. 254—98)

This invention relates to improvements in lifting jacks and it consists of the matters hereinafter described and more particularly pointed out in the appended claims.

5 The jacks with which my invention is more particularly concerned are of the kind embodying therein a standard, in which is mounted two telescoping screw members, which are adapted to be successively projected out of and retracted into the 10 standard.

One of the objects of the present invention is to provide a simple braking mechanism for the outer threaded member of the telescoping screws so as to hold said outer threaded member against 15 rotation at certain times in the operation of the jack for its intended purpose.

Another object of the invention is to provide a mechanism of this kind which is distorted from its original condition during its insertion into its 20 intended position in the standard and is held in this distorted condition and against removal by the outer member of the screw with which it engages with the braking action desired.

The above mentioned objects of the invention as 25 well as others, together with the many advantages thereof, will more fully appear as I proceed with my specification.

In the drawing:

Fig. 1 is a view in elevation of a double screw 30 jack embodying the preferred form of the invention, with certain parts broken away to more clearly disclose the structure thereof;

Fig. 2 is a horizontal transverse section through the jack as taken on the line 2—2 of Fig. 1; and

35 Fig. 3 is a top plan view of the braking shoe or spring in its original condition and illustrates in dotted lines, the shape into which it is distorted when applied in position in the jack standard.

Referring now in detail to that embodiment of 40 the invention, illustrated in the accompanying drawing:

1 indicates the tubular standard of the jack having a horizontally extended base 2 at its bottom end and upon which the jack stands upright.

45 At the top end of the standard is preferably an integral yoke 3 enclosing a downwardly facing bevel gear 4, said gear having a hub at its top end. An antifriction thrust bearing 5 is disposed between the bottom of said gear and the top end of 50 the tubular standard. The gear 4 is provided with internal threads and in effect forms the rotating nut of the jack.

To rotate the gear 4, a meshing pinion 6 is journaled in a laterally extending tubular boss 7 55 forming a part of the yoke 3, the pinion 6 being

so constructed as to receive the usual handle (not shown) whereby it may be turned in the desired direction.

8 indicates the outer tubular screw of the jack. This screw is externally threaded for engagement 60 with the internal threads of the gear 4 and is internally threaded to receive the inner screw 9. The external threads of the outer screw terminate short of the bottom end of the screw so that said screw cannot be projected entirely out of the gear 65 4 in the operation of the jack. The top end of the inner screw carries a swiveling cap 10.

To impose a braking action on the outer screw so as to hold it against turning with the gear 4 during the initial part of its rotation and thus 70 cause projection of the outer screw, which carries the inner one therewith, I provide the following simple arrangement:

In the top end of the standard, in opposite sides thereof, in the plane of the yoke 3, are formed 75 openings 11—11 that communicate with the interior of the standard. In connection therewith, I provide a braking element 12 in the form of a bow shaped spring including an arched center portion 13 and oppositely extending straight end 80 portions 14—14. This spring may be entered into the standard from one side thereof through one of the openings 11 until each end part extends through an associated opening. Said spring, of course, is inserted into place before the outer screw 85 is assembled in place.

In assembling the screws 8 and 9 into the standard, this is done from the bottom end of the standard. During this assembly, the arched portion of the spring is distorted or deformed into 90 substantially a semi-circular shape (as shown in dotted lines in Fig. 3) so that the top end of the outer screw may pass the same in the insertion of the screw from the bottom end of the standard. The distortion of the spring may be accomplished 95 from the top end of the standard, before assembly of the gear 4, merely by reaching in from the top end of the standard with the finger or a suitable tool and pressing said arch portion toward one side of the interior of the standard.

100 With the spring thus distorted, the assembled screws are inserted in place from the bottom end of the standard, the spring being held distorted until the top end of the outer screw is passed beyond the same. With the screws in place, the 105 spring will act as a spring pressed shoe having a good snug frictional engagement with the periphery of the external threads of the outer screw.

When the jack is being operated in lifting a load, the spring so engages the periphery of the 110

outer screw as to prevent its turning. Thus the rotation of the gear 4 will cause the screws to be projected and lift the load. When the outer screw reaches the limit of its projection, it locks to and turns with the gear 4 when the inner screw is telescopically projected from the outer one. When it is desired to lower the load, the operation is just the reverse of that described.

It is pointed out that the spring employed is wide enough to constantly engage at least two of the threads on the outer screw. Thus as the screw travels past the spring, a surface engagement providing that friction necessary to hold the screw against free turning is obtained.

15 Should the spring become worn beyond usefulness, the outer screw is turned so as to be withdrawn from the bottom of the gear 4 and when the screw has passed below the spring, the worn spring is removed and replaced by a new one.

20 Thereafter the screw and gear are replaced and the jack is again ready for service.

The improved braking device consists of but a single element that may be made at a relatively low cost and it is easy to assemble into its intended position in the jack.

While in describing the invention, I have referred in detail to the form, arrangement and construction of the various parts of the jack, the same is to be considered only in an illustrative sense so that I do not wish to be limited thereto except as may be specifically set forth in the appended claims.

75

I claim as my invention:

1. In a jack of the kind described, the combination of a standard, a nut rotatably mounted on the top end of the standard, means for rotating said nut, a screw disposed in the bore of said standard and operatively engaged in the nut, a flat spring element having straight ends arranged in openings in substantially opposite sides of the standard and including a curved portion between said ends disposed in the bore of said standard and having a braking engagement with a peripheral portion of said screw at least one of said spring ends being so arranged in its opening as to be reachable in removing the spring from the standard. 80

2. In a jack of the kind described, the combination of a tubular standard, a nut rotatably mounted on the top end of the standard, a screw disposed in the bore of said standard and operatively engaged in the nut, there being openings in wall portions of said tubular standard, a flat spring element insertable into the bore of said standard through one of said openings and having substantially straight ends engaged in said openings after being so inserted and including a distorted curved portion between said ends disposed in said bore and frictionally engaged with a portion of the screw. 95
